UNITED STATES PATENT OFFICE.

PHILIP T. SHARPLES, OF ST. DAVIDS, PENNSYLVANIA, ASSIGNOR TO SHARPLES SPECIALTY COMPANY, OF WEST CHESTER, PENNSYLVANIA, A CORPORATION OF PENNSYLVANIA.

CENTRIFUGAL SEPARATOR.

1,277,653.

Specification of Letters Patent. Patented Sept. 3, 1918.

Application filed November 6, 1917. Serial No. 200,519.

To all whom it may concern:

Be it known that I, PHILIP T. SHARPLES, a citizen of the United States, residing at St. Davids, in the county of Delaware, and 5 State of Pennsylvania, have invented certain Improvements in Centrifugal Separators, of which the following is a specification.

My invention relates to the separation of substances of different specific gravities by 10 centrifugal force, more particularly to the clarification of liquids or the separation of solids or semi-solids from liquids when the substances are in small amounts, and it is characterized by the use of a revolvable bowl 15 having sections of different diameters, the upper section of larger diameter for holding the separated solids preferably being separable from the lower section, which preferably has a closed bottom for retaining the 20 liquid.

The improvements are conveniently embodied in an inner bowl of comparatively small capacity, which is adapted to be inserted in and withdrawn from the bowl of a 25 usual type of separator, but a single bowl machine may be used.

In the accompanying drawings, Figure 1 is a vertical sectional view of a centrifugal separator embodying my improvements; 30 Fig. 2 is a vertical sectional view of the detached inner bowl; Fig. 3 is a top plan view of the inner bowl; Fig. 4 is a vertical sectional view of a modified form of bowl constructed according to my invention; Fig. 5 is a vertical sectional view of a further form 35 of the invention; and Fig. 6 is a view taken on the line 6—6 of Fig. 5.

The machine shown in Figs. 1 to 3 of the drawings, for the purpose of illustrating a 40 form in which my invention may be used, comprises a frame 1 provided with the case 2 in which a bowl 3 is suspended and revolved by a shaft 4 carried by the bearings 5, the bowl being removable from the case by 45 uncoupling it from its supporting shaft and removing the pan 6 from its detachable connection with the case. The bowl bottom 7, which is removable, has thereon the hollow boss 8. This boss is revolvable in the part 9 carried by a hollow plug 10, which is screwed 50 into the bottom of the case and passes the substance to be separated to the boss and thence to the interior of the bowl, in the usual operation of this known type of ma- 55 chine.

In accordance with my invention, a bowl 11 with an imperforate circular wall has the substance to be separated placed therein and this bowl with its contents is placed in the bowl 3, the bottom 7 having been removed 60 to permit the insertion of the inner bowl and then replaced to provide a support for the same.

The inner bowl 11 comprises the cylindrical bottom section 12, with an exterior diameter smaller than the interior diameter of the bowl 3, and having a closed bottom 13, with a flange 14 adapted to fit loosely in the bowl 3, in combination with a cylindrical top section 15 having an exterior surface 65 adapted to make a loose fit with the interior of the bowl 3; the bottom of the section 15 being provided with the downwardly tapered section 16 and the threaded collar 17 which screws on the threaded top of the section 12 and the top of the section 15 being provided with the upwardly tapered section 18 forming an inwardly extending lip 70 or rim.

The inner bowl 11, with its contents to be 80 separated contained in the bottom section 12, is placed in the bowl 3 by removing and replacing the bottom 7. The assembled machine is then operated, with the result that the contents of the inner bowl rises therein, 85 separating from the liquid and forming an outer stratum which lodges in the upper section 15. Upon the completion of the operation, 90 the clarified liquid falls back into the section 12. Upon dissociating the parts of the machine and removing the inner bowl, the parts 12 and 15 may be separated with the clarified liquid held in the section 12 and the matter separated therefrom held in the section 15. 95

As illustrated in Fig. 4, a special bowl 20 may be substituted for the regular type bowl 3, in a machine of the desired capacity, such special bowl being suspended and revolved by the spindle 4 and having the bottom boss 21 which revolves in the controlling mechanism 9. The bowl 20 comprises the bottom section 22 having the closed bottom 23 and the top section 24 of larger diameter than 100 the section 22, this top section having the tapered bottom part 25 provided with a part 26 which screws on the top of the part 22. 105

As in the use of the inner bowl 11, the matter to be separated is placed in the bowl 110.

20 by separating the parts 22 and 24, which are then connected. The bowl having been placed in the machine and revolved at the required speed, the contents rise therein and 5 the constituent parts of different specific gravities are separated. The heavier solid or semi-solid matter lodges in the section 24, and the lighter matter falls back into the section 22 upon completing the operation, 10 when the bowl is removed from the machine and its parts with their respective contents are separated.

The bowl may be provided with means 15 for holding and may hold a container for the substances to be separated. A form of such means is illustrated in Figs. 5 and 6, in which the bowl 11 is provided with the radial wings 27 converging downwardly and providing bearings for supporting the 20 downwardly tapered cup 28, adapted to be inserted and withdrawn through the bowl's top opening 29. The wings serve the purpose not only of supporting the cup, but also of accelerating the movement of the substances and facilitating their separation.

The substances to be separated having been placed in the cup and the latter being held in the desired position by the wings, upon operating the assembled machine, the 30 substances contained in the cup are carried over its top and thrown outwardly by centrifugal force, the heavier solid or semi-solid matter lodging in the upper bowl section 15 and the lighter liquid falling into 35 the section 12, thus keeping the intermingled substances, or the solid matter to be removed, from the section 12, and avoiding the lodgment of such solid matter therein.

The substances having been separated 40 within the bowl 11, the sections 12 and 15 are separated, and the clarified or purified liquid and the solid matter are removed.

Having described my invention, I claim:

1. In a centrifugal machine, a revoluble 45 vertical bowl having an imperforate circular wall, with a bottom section and a top section of larger diameter than said bottom section, said bottom section being adapted for delivering its contents to said top section to 50 effect separation therein when said bowl is revolved about its axis and said top section being adapted for retaining therein separated solid or semi-solid matter while permitting the liquid to be drained therefrom 55 into said bottom section, in combination with means for supporting said bowl and revolving it about its axle.

2. In a centrifugal machine, a revoluble 60 vertical bowl having an imperforate circular wall with separable upper and lower sec-

tions, the upper section being of larger diameter with an inwardly extending lower part adapted for supporting solid or semi-solid matter separated therein by centrifugation while draining the liquid therefrom and the lower section being adapted for discharging substantially all its contents into said upper section by centrifugation, in combination with means for supporting said bowl and revolving it about its axis.

3. In a centrifugal machine, a revoluble vertical bowl, means for revolving said bowl about its axis, and a second bowl with an imperforate wall held in and adapted to be removed from said bowl first named, said second bowl having an upper section of larger diameter than and adapted to drain its liquid contents into a lower section while retaining solid or semi-solid matter separated from said liquid and said lower section being adapted to deliver its contents into said upper section when said bowl is revolved.

4. In a centrifugal machine, a revoluble bowl, means for revolving said bowl about its axis, and a second bowl telescoped in and removable from said bowl first named, said second bowl having a closed bottom and an imperforate circular wall with a top section adapted to retain solid contents, of larger 85 diameter than a bottom section thereof, said bottom section adapted to receive the liquid contents from said top section.

5. In a centrifugal machine, a revoluble tubular bowl, means for revolving said bowl about its axis, and a second bowl held in and removable through an end of said bowl first named, said second bowl having an imperforate circular wall with an upper section adapted to retain solid contents, of 90 larger diameter than a lower section thereof, adapted to receive the liquid content from said upper section, said upper section having inwardly extending ends.

6. In a centrifugal separator, the combination with a revoluble bowl having an enlarged upper section containing wings, of a container supported in said bowl and adapted for so holding substances that they may be thrown therefrom into said enlarged 105 section by centrifugal force.

7. In a centrifugal separator, the combination with a revoluble bowl containing downwardly converging wings, with a downwardly tapered container supported in 110 said bowl by said wings.

In testimony whereof I have hereunto set my name this 2nd day of November, 1917.

P. T. SHARPLES.
